UNITED STATES PATENT OFFICE.

ARTHUR BARKER, OF LONDON, ENGLAND, ASSIGNOR TO GEORGE THOMAS HINE, OF
WESTMINSTER, ENGLAND.

CARBURETER FOR INTERNAL-COMBUSTION ENGINES OR MOTORS.

979,409.

Specification of Letters Patent. Patented Dec. 27, 1910.

Application filed August 19, 1908. Serial No. 449,358.

To all whom it may concern:

Be it known that I, ARTHUR BARKER, engineer, a subject of the King of Great Britain, and a resident of London, England, (whose post-office address is 20 Meads road, Wood Green, London, England,) have invented certain Improvements in Carbureters for Internal-Combustion Engines or Motors, of which the following is a specification.

The present invention relates to carbureters or vaporizers and is especially designed to provide an improved method of vaporizing paraffin or other hydrocarbons and effectually combining them with the atmospheric air so as to form a highly charged vapor for exploding in internal combustion engines or motors.

The oil, together with air, is drawn through a series of one or more perforated screens situated within the apparatus, and capable of rapidly vibrating so that the oil becomes sprayed or atomized (*i. e.* divided up into a fine state), and at the same time the air becomes carbureted thereby. The intimate mixture of air and oil so formed is subsequently passed through heated passages whereby the oil becomes fully vaporized and the intermixture is rendered more complete.

A particular form of construction will now be described by way of example, with particular reference to the accompanying drawings.

In the drawing a vertical sectional view of a carbureter is illustrated embodying one form of my invention.

The carbureter or vaporizer consists of a hollow cylindrical vessel 1 of suitable diameter and height fitted with a valve chamber 2 preferably at the top. The latter is closed by a cap 3 which serves as a means of connection to the oil or other liquid fuel supply, and is provided with a seating for the oil valve portion 4 of a duplex or compound valve around the spindle 5 of which is a sleeve 6 loosely fitted, said sleeve being attached to an oil and air mixture valve 7. The valve 7 is supported on a spring 8 attached to the oil valve spindle 5 the lower end of which may rest on the top of a cap 9, the interior of which is bored out so as to permit of its resting on a projection 10 attached to the top of the vaporizing or heating appliance 11. A spring 12 is inter-

posed between the projection 10 and the top of the cap 9 and a series of gauze or like disks 13 of a diameter equal to that of the interior of the vessel 1 are suitably attached to the exterior of said cap 9.

The whole or a portion of the exhaust gases will be introduced into the heating appliance 11 through a pipe 14 and will circulate through said appliance in such a manner that the lower part receives more heat than the upper part. For this purpose a partition 15 may be used to more or less completely separate the lower and upper parts. The air can be admitted to the carbureter through the ports at 16, 17 and 18 or either of them. The port 16 comprises a series of holes bored through a neck on the valve chamber 2, and controlled by a rotatable ring 19, having holes which can be adjusted so as to either correspond with or close the holes in said port 16. The port 18 may also be controlled by a rotatable disk 20. A shoulder 21 on the spindle 5, is slotted vertically to receive a disk 22 attached to an arm 23, which bears against a spring 24 surrounding a rod 25 fixed by an arm 26 to the outside of the valve chamber 2. Said spring 24 can be adjusted by nuts 27. The disk and spring-controlled arm 23 serve to keep the valve spindle 5 normally raised and thus retain the mixture valve 7 and oil valve 4 in their closed positions. During the suction of the piston, the mixture valve 7 is drawn from its seat, and pressing on the spring 8 causes the latter to bear against the collar 28, and thus lower the spindle 5 and open the oil valve 4, a certain portion of oil thus being admitted into the valve chamber 2, where it mixes with the air drawn in from one or more of the ports. The amount of suction may be regulated by adjusting these air inlets, or by a throttle or other means fixed to the induction pipe. The oil passes through the mixture valve 7 and drops on to the first of the gauze disks 13, a funnel 29 being provided to direct the oil. This and the other disks will during every suction stroke, be in a state of very rapid vibration owing to the intermittent compression of the spring 12 during the suction stroke of the piston, and the subsequent release of said spring. This effect will be gained satisfactorily even when there is a space of half an inch or so between the spindle head and the cap 9, it not being

essential for the latter to support the former. The controlling action of the spindle 5 can be governed in some degree by means of the spring 24, which controls the disk 22, and 5 causes the latter to close the valve 7 when the suction stroke of the engine ceases. By this means, the oil will be in a state of fine division when it has passed through the gauze disks 13. It then falls on to the top 10 surface of the heating device 11, and passes down through holes (preferably oblique) in the flanges 30, 31, 32 into the cylinder inlet chamber 33 from which it is admitted to the cylinder. Owing to the fact that the lower 15 part of said heating device is hotter than the upper part, the heavier portions of the oil which flow toward the bottom are properly vaporized without leaving any deposit, the lighter portions being vaporized in their 20 passage over the less heated upper parts of the heating chamber.

I claim:—

1. In a vaporizer or carbureter, the combination of a casing, atomizing means therein including a screen, a yielding support for said means, an oil valve; a mixture valve arranged to be operated by suction of the engine, and mechanism whereby movement of said mixture valve serves to operate said 25 oil valve and actuate said means in opposition to its yielding support.

2. In a vaporizer or carbureter, the combination of a casing, atomizing means therein including a screen, a yielding support for said means, an oil valve having a stem engaging said means, a mixture valve arranged to be operated by suction of the engine, and mechanism operatively connecting said mixture valve with said stem where- 30 by said stem and said means are operated upon movement of said mixture valve.

3. In a vaporizer or carbureter, the combination with a casing, of a plurality of super- 35 posed screens for atomizing the oil delivered thereto, a member carrying said screens and provided with a recess in its lower end and closed at its upper end, a post projecting into said recess, a spring interposed between the end of said post and the closed 45 upper end of said recess, means separate from and engaging said member and operated by suction of the engine to act in opposition to said spring to vibrate said screens, and means for feeding oil to the uppermost 50 screens.

4. In a vaporizer or carbureter, the combination with a casing, a plurality of super- 55 posed screens for atomizing the oil, a member carrying said screens and provided with a recess in its lower end and closed at its upper end, a post projecting into said recess, a spring in said recess engaging the end of said post and the closed upper end of said member, a valve spindle engaging said member, means connected with said spindle and

operated by a suction of the engine to act in opposition to said spring to vibrate said screens, and a valve on said spindle for admitting oil to the uppermost screens.

5. In a vaporizer or carbureter, the combination with a casing provided with a valve chamber and oil and air inlets delivering thereto, said casing also having a vaporizing chamber communicating with the engine, a plurality of superposed screens disposed in 75 said vaporizing chamber to receive the oil from said valve chamber, a member supporting said screens, a spring acting on said member, a valve spindle engaging said member and provided with an oil valve closure 80 regulating the passage of the oil through said oil inlet, a mixture valve slidably mounted on said spindle for regulating admission from the valve chamber to the vaporizing chamber and arranged to be 85 operated by suction of the engine, and means interposed between said mixture valve and spindle for normally maintaining said mixture valve seated and serving when said valve is open to engage said spindle with 90 said member in opposition to said spring to vibrate said screens.

6. In a vaporizer or carbureter, the combination with a casing provided with a vaporizing and a valve chamber, a screen in 95 said vaporizing chamber for atomizing the oil, a member carrying said screen and supporting it in the path of the oil, a spring supporting said member, a valve spindle engaging the top of said member, means for 100 controlling movement of said spindle, a mixture valve including a seat and closure with the closure disposed in a manner to be acted upon by suction of the engine, said closure being slidably mounted on said 105 spindle and controlling communication between said chambers, means associated with said spindle and closure for normally seating the closure and transmitting opening movement thereof to spindle, said valve 110 chamber being provided with an air inlet and an oil inlet, said spindle having a closure for said oil inlet, and means for controlling said air inlet.

7. In a vaporizer or carbureter, the combination with a casing having a valve chamber provided with air and oil inlets and a vaporizing chamber communicating with said valve chamber and with the engine and provided with a heating device adjacent to 115 the point of connection with the engine, a screen in said vaporizing chamber, a spring support for said screen, a valve spindle arranged to vibrate said screens against the action of said spring support, said valve 120 spindle having an oil valve for controlling oil admission through said oil inlet, a mixture valve slidably mounted on said spindle and disposed in a manner to be acted upon by suction of the engine, means associated 125 130

- with said mixture valve and spindle for transmitting movement thereof to said screen and normally seating said mixture valve, means for controlling air admission 5 to said valve chamber, means for regulating movement of said spindle, said casing having an air inlet adjacent said heating device, and means for controlling air admission therethrough as the mixture passes over 10 said device.
8. In a vaporizer or carbureter, the combination with a casing provided with a valve chamber having an air and oil inlet and a vaporizing chamber communicating with 15 said valve chamber, a screen in said vaporizing chamber, a valve arranged to be operated by the suction of the engine and controlling communication between said chambers, a spindle associated with said valve 20 and screen in a manner to vibrate the latter, said casing communicating with the engine and being provided with a partition substantially dividing said vaporizing chamber into upper and lower portions, and pipes 25 delivering exhaust gases into the lower portions, said partition having flanges provided with openings through which the mixture passes, and a controllable air inlet delivering to said vaporizing chamber below said 30 flanges.
9. A vaporizer or carbureter comprising in combination, a casing provided with a valve chamber for admission of oil and air, a valve stem in said chamber provided 35 with a valve for controlling admission of oil, said casing having a vaporizing chamber communicating with said valve chamber and with the cylinder of the engine, a device in said vaporizing chamber 40 for sub-dividing the oil and having a yielding support and arranged to be engaged by said stem, an admission valve on said stem arranged to be acted upon by suction of the engine to be opened thereby, and an 45 element through which said admission valve acts on said stem to operate said device in opposition to its yielding support.
10. A vaporizer or carbureter comprising in combination, a casing communicating 50 with a source of supply of air and oil and
- with the engine, a perforated partition in said casing receiving the oil on its upper surface, other perforated partitions below said partition, a heating chamber, a connection between said heating chamber and the exhaust of the engine, and a partition in said heating chamber for maintaining first named partition at a lower temperature than the lower partitions. 55
11. In a vaporizer or carbureter, the combination of a casing, of atomizing means therein including an element having openings, a yielding support for said means, an oil valve provided with a stem engaging said means, a spring normally closing said oil 60 valve, a mixture valve arranged to be opened by suction of the engine, and a spring through which said mixture valve acts to actuate said stem and operate said means in opposition to its yielding support. 70
12. In a vaporizer or carbureter, the combination of a casing, of atomizing means therein including a screen disposed in the path of the oil, a yielding support for said means, a mixture valve normally held seated 75 by said yielding support and having a certain area arranged to be acted upon by suction of the engine to open said valve and operate said means in opposition to said yielding support, and a spring through 80 which said mixture valve acts to operate said means.
13. In a vaporizer or carbureter, the combination of a casing, of atomizing means therein including a screen disposed in the 85 path of the oil, a spring held oil valve, and a mixture valve normally held seated by said yielding support and oil valve spring, and operatively connected with said oil valve, said mixture valve having a surface area arranged to be acted upon by suction of the engine to open said mixture and oil valves and operate said means against the action of 90 its yielding support.

In testimony whereof I affix my signature 95
in the presence of two witnesses.
